UNITED STATES PATENT OFFICE.

BARKER C. YOUNG, OF BOSTON, MASSACHUSETTS.

IMPROVEMENT IN GAITER-BOOTS.

Specification forming part of Letters Patent No. 159,135, dated January 26, 1875; application filed December 19, 1874.

To all whom it may concern:

Be it known that I, BARKER C. YOUNG, of Boston, of the county of Suffolk and State of Massachusetts, have invented a new and useful Improvement in Gaiter-Boots; and do hereby declare the same to be fully described in the following specification, and represented in the accompanying drawings, of which—

Figure 1 is a top view; Fig. 2, a side elevation; and Fig. 3, a rear view of a gaiter-boot, provided with my invention.

The invention or improvement relates to such gaiter-boots as have two fore and back leg-flaps, and a fastening strap and buckle to the fore flap, the said invention consisting in such a boot, provided not only with a button fixed to the middle of the back flap, but with a button hole in the strap, the said button-hole being to receive the said button, and with it perform two functions—viz., not only a means of preventing the strap from slipping up or down in the back-flap, but of fastening the strap to the back-flap, independently of the buckle, and to operate with it, in securing the shoe on the foot of a person.

I am aware that in such a shoe it is not new to put on the back-flap a loop for the strip to be run through, such loop being simply to prevent the strap from rising or falling, or working up and down on the flap, all being as shown in the United States Patent No. 145,801, dated December 23, 1873. Consequently I do not claim a gaiter-boot provided with such a loop, so arranged with its back-flap and strap.

In the drawings, A denotes a gaiter-boot, provided with one fore leg-flap, a, and one rear leg-flap, b, and with a strap, c, to one

portion or fly of the fore flap, and a buckle, f, to the other fly of said flap, all as shown.

In carrying out my invention I fix to the lower part and middle of the back-flap a button, d, and make in the strap a button-hole, e, to button upon said button when the flaps are drawn together upon the legs of an individual.

It sometimes happens that while a person may be walking the buckle may become accidentally lost, or broken so as to be useless for holding the strap. With the shoe provided with the button-hole and button, in combination with the strap and its buckle, as set forth, the back and fore flaps will be held together on the inner side of the shoe, in case of breakage or loss of the buckle. Furthermore, the button and button-hole are manipulated much easier than the loop, from which the strap has first to be entirely withdrawn before the shoe can be put on or taken off the foot of a person.

The return of the strap to and through the loop is often attended with much inconvenience when the shoe is on the foot, but with the button-hole and button the strap can readily and easily be connected or disconnected.

I claim—

In combination with the gaiter-boot A, provided with the two leg-flaps a b, and the strap c, and its buckle f, arranged as described, the button d, fixed to the middle of the back-flap, and the button-hole e made in the strap, all substantially as specified.

B. C. YOUNG.
